[57] CLAIM

The ornamental design for a height adapter for a storage battery container, as shown and described.

DESCRIPTION

FIG. 1 is a front perspective view of a height adapter for a storage battery container showing our new design, the broken line showing of the storage battery is an environmental element included for illustrative purposes only and forms no part of the claimed design;

FIG. 2 is a top plan view thereof;

FIG. 3 is a bottom plan view thereof;

FIG. 4 is a front elevational view thereof, the rear elevational view being a mirror image;

FIG. 5 is a left side elevational view thereof, the right side elevational view being a mirror image;

FIG. 6 is a front perspective view of a height adapter for a storage battery container showing a second embodiment of our new design, the broken line showing of the storage battery is an environmental element included for illustrative purposes only and forms no part of the claimed design;

FIG. 7 is a top plan view thereof;

FIG. 8 is a bottom plan view thereof;

FIG. 9 is a front elevational view thereof, the rear elevational view being a mirror image;

FIG. 10 is a left side elevational view thereof, the right side elevational view being a mirror image.

FIG. 1

FIG. 2

FIG. 3
